(57) **CLAIM**

The ornamental design for a display screen with a graphical
user interface for a herd management system, as shown and
described.

DESCRIPTION

FIG. 1 is a front view of a display screen with a graphical
user interface for a herd management system, showing my
new design;

FIG. 2 is another embodiment thereof;

FIG. 3 is another embodiment thereof;

FIG. 4 is another embodiment thereof;

FIG. 5 is another embodiment thereof;

FIG. 6 is another embodiment thereof;

FIG. 7 is another embodiment thereof;

FIG. 8 is another embodiment thereof;

FIG. 9 is another embodiment thereof;

FIG. 10 is another embodiment thereof;

FIG. 11 is another embodiment thereof; and,

FIG. 12 is another embodiment thereof.

The broken line showing of a display screen with graphical
user interface is included for the purpose of showing portions
of the article which form no part of the claim.

1 Claim, 12 Drawing Sheets
